A cross-sectional diagram of a soil profile. The top layer is a thin, light-colored layer. Below it is a thick, dark, hatched layer. A vertical structure, labeled 'B', is embedded in the dark layer. Above this structure, a horizontal pipe or tube, labeled 'H', extends downwards into the dark layer. The bottom of the diagram shows a thin, light-colored layer.

UNITED STATES PATENT OFFICE.

BENJAMIN F. HALL, OF SALEM, MASSACHUSETTS, ASSIGNOR OF ONE-HALF
TO ZINA GOODELL, OF SALEM, MASSACHUSETTS.

PUNCHING-MACHINE.

SPECIFICATION forming part of Letters Patent No. 706,552, dated August 12, 1902.

Application filed September 21, 1901. Renewed July 9, 1902. Serial No. 114,959. (No model.)

To all whom it may concern:

Be it known that I, BENJAMIN F. HALL, a citizen of the United States, residing at Salem, in the county of Essex and State of Massachusetts, have invented certain new and useful Improvements in Punching-Machines, of which the following is a specification.

This invention relates to improvements on the United States patent granted to me for punching-machines September 17, 1901, No. 682,686, and it is carried out as follows, reference being had to the accompanying drawings, wherein—

Figure 1 is a side elevation of the machine, showing the balance-wheel and cone-pulley removed. Fig. 2 is a horizontal section on the line 2 2 in Fig. 1. Fig. 3 is a vertical section on the line 3 3 in Fig. 2, showing the adjustable feed mechanism. Fig. 4 is a vertical section on the line 4 4 in Fig. 2. Fig. 5 is a plan view, partly in section, showing mechanism for operating the feed-point in a vertical direction. Fig. 6 is a similar view showing mechanism for operating the feed-point in a horizontal direction. Fig. 7 is a front view of the die-holder and presser-foot, showing a portion of the latter, the work-supporting plate, punch-plate, and feed-point in section. Fig. 8 is a side elevation of the arm for adjusting the length of the feed, and Fig. 9 is a detail side elevation of the eccentric-pin for vertically adjusting the feed-point and its carrier.

Similar letters refer to similar parts wherever they occur on the different parts of the drawings.

In the drawings, A represents the base portion of the frame of the machine, and A' is the gooseneck thereon, as usual.

40 B represents the work-supporting plate. C is the rotary driving-shaft, journaled in bearings in the frame portion A and provided in one end with a cone-pulley D, to which a rotary motion is imparted by means of belt-power, as usual.

On the shaft C is an eccentric E, surrounded by a strap e, the rear end of which is pivotally connected to the lower end of a bell-crank lever F, pivoted at f to the rear upper portion of the gooseneck A', like that shown and described in my aforesaid Letters Patent.

The front end of the lever F is pivotally connected to the upper end of the die-holder bar G, which is guided in bearings in the forward end of the gooseneck A', like that shown 55 and described in my aforesaid Letters Patent.

H is the die, secured in a suitable manner to the lower end of the die-holder bar, as is common in devices of this kind.

The feed device for automatically and intermittently feeding the goods to the die during the punching or perforating operation is what is usually termed a "four-motion positive feed" and is constructed as follows: It consists of a serrated segmental feed-point I, 60 secured to a feed-point carrier or lever K, which latter is pivoted at k to a link L, the rear end of which is pivotally connected to a block l, adjustable in a grooved segment M, which is hung at m on a stationary pivot. A 65 rocking motion is imparted to said grooved segment M by means of an eccentric N, secured to the rotary driving-shaft C and surrounded by a strap N', the forward end of which is pivotally connected at m' to the 70 grooved segment M, as shown.

For the purpose of adjusting the length of feed I move the block l up or down within the grooved segment M, and such adjustment I accomplish by means of a lever O, secured 80 to a spindle O', frictionally journaled in a bearing in the frame A and having secured to its inner end a lever O'', the rear end of which is pivotally connected to a link O³, the upper end of which is pivotally connected to 85 the link L or block l, as shown in Figs. 2, 3, 4, 5, and 6. Integral with the adjusting-lever O is made a graduated segment O⁴, by means of which the degree of the feed can readily be ascertained.

In machines of this kind it is necessary to adjust the vertical movement of the feed-point and its carrier relative to the thickness of the goods, and this I accomplish by the following mechanism: On the driving-shaft 95 C, I secure a cam or eccentric P, adapted to actuate a forked rocking lever Q, the forward end of which is pivotally connected at k' to the lower end of the feed-point carrier or lever K, as shown. The said lever Q is hung 90 upon an eccentric-pin R, the ends of which are frictionally journaled in bearings in the

sides of the frame A, as shown. To the outer end of the pin R is secured a lever S, and by means of the latter the eccentric-pin R may be turned so as to raise or lower the fulcrum of the rock-lever Q, and by such adjustment the feed-point-carrier lever and its feed-point are correspondingly raised or lowered to compensate for the thickness of the goods that is to be perforated.

10. In Fig. 7, T represents the vertically-yielding presser-foot bar, to which is suitably journaled the rotary presser-foot f, the lower portion of which is held in yielding contact with the feed-point I and the goods located 15 between the latter and said rotary presser-foot, as is common in machines of this kind.

In connection with this machine I use a suitable gage, against which the edge of the work is guided during the punching operation, such gage being, however, not shown in the drawings, as it is a well-known feature in machines of this kind.

15. The operation of this my improved punching or perforating machine is as follows: The article to be perforated is placed upon the table B, with its edge against a suitable gage thereon, and after the presser-foot is raised it is allowed to drop onto the article and be held in contact therewith by spring-pressure, 20 as usual. The machine is then set in operation by imparting a rotary motion to the driving-shaft C, causing the die-holder bar and its die to be vertically reciprocated for the purpose of punching or perforating the article 25 and causing the feed device to intermittently feed the said article the desired distance while the die is raised above the work, and 30 so on during the operation of the machine.

What I wish to secure by Letters Patent and claim is—

1. In a punching or perforating machine, in combination, a rotary driving-shaft and mechanism for imparting a reciprocating motion to a die-carrier, a rocking feed-point and carrier, means for positively actuating and controlling the amount of feed of the latter, a rock-lever actuated by a cam or eccentric on the rotary driving-shaft, and pivotally connected to the rocking feed-point carrier, said rock-lever being pivotally arranged upon an adjustable eccentric-pin for the purpose of adjusting the vertical movement of the feed-point carrier substantially as and for the purpose set forth.

2. In a punching or perforating machine, a four-motion positive and adjustable feed device, consisting in combination a rotary driving-shaft, an eccentric thereon, a pivoted grooved segment actuated by said eccentric, a block adjustable in said segment, a rocking feed-point carrier, pivotally connected to said block, means for adjusting the latter in the segment, a rock-lever actuated by an eccentric on the driving-shaft and pivotally connected to the feed-point carrier, and an adjustable eccentric-pin upon which said lever is hung for the purpose of adjusting the vertical motion of said feed-point carrier substantially as herein set forth and described.

In testimony whereof I have affixed my signature in presence of two witnesses.

BENJAMIN F. HALL.
